Primary Examiner — Eric L Goodman*Assistant Examiner* — Kyle A. Edelmaier(74) *Attorney, Agent, or Firm* — JEEN IP LAW, LLC(57) **CLAIM**

The ornamental design for a handheld fan, as shown and described.

DESCRIPTION

FIG. 1 is a front, right and top perspective view of a handheld fan, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is an exploded perspective view thereof.

The broken lines shown in the drawings illustrate portions of the handheld fan that form no part of the claimed design.
